ART OF FRACTIONAL DISTILLATION.

Application filed July 21, 1922. Serial No. 576,611.

Our invention relates to fractional distillation and more particularly to the fractionation of hydrocarbon mixtures of the character of petroleum, having a large and 5 indefinite number of constituents of increasing boiling points to produce simultaneously and continuously therefrom, a plurality of fractions each comprising more or less complex mixtures in and of themselves and each 10 of said fractions containing substantially no constituents boiling above the upper limit of a predetermined range for said fraction.

In the practice of fractional distillation in the chemical industries generally, the conditions involved and the problems encountered 15 are relatively clear cut and simple. In the case of alcohols and esters, etc., compounds and mixtures possessing a few very definite and well separated boiling points only are 20 concerned; similarly in the case of coal-tar distillates, only a relatively few compounds, with definite and practicably spaced boiling lines of separation are dealt with.

On the other hand, in the petroleum industry 25 try the material in operation is a complex mixture of a legion of closely boiling compounds from very simple hydrocarbons on up to members of such complexity that their precise structure has not even yet been determined. Moreover, the lower and higher 30 prima facie limits for such mixtures are extended by the fact that there are tenaciously held by solution further members whose normal physical state apart would be gaseous in the case of the lowest members and solid in the case of the higher. Further 35 complications arise from the fact that beyond the simplest members, for hydrocarbons of a given number of carbon atoms, various isomers occur, and all these bring in 40 complex overlappings in boiling points.

In the distillation of petroleum then, the 45 boiling point temperature, starting at its lower limit, mounts on a progressively sliding scale. If the distillate coming off at a given temperature were precisely only the hydrocarbon normally boiling at that temperature, close separations could be made, but with petroleum hydrocarbons such is far 50 from the case, for by reason of the peculiar

attractive force between these hydrocarbons, the distillate at a given temperature includes hydrocarbons of normal boiling point both considerably lower and higher than would be expected.

This situation has presented quite a problem, for as a result of such conditions, in the distillation of crude oil, for instance, where distillate cuts are taken for naphtha, for water white, for gas oil, etc., the naphtha 55 cut will contain hydrocarbons which should be in the water white fraction, and the water white cut will contain hydrocarbons which should be in the naphtha fraction and in the gas oil fraction, and the gas oil cut will contain hydrocarbons which should be in the water white fraction, etc. It is then necessary to re-distill these cuts in the effort to separate out and place the stray components, and in the re-running it becomes necessary 60 to take a "heart-cut" at the overlapping range between the naphtha and water white fractions, etc., for again further re-distilling, and in some cases this must be further repeated. And even with the best overhead 65 equipment heretofore used, a sharp separation is not realized.

By our invention we have now succeeded in attaining direct separations wholly or substantially free from overlap. The invention will be fully understood from the following description, reference being had also to the accompanying drawing, in which—

Fig. 1 is a side elevation, partly in section, of one form of apparatus contemplated in 75 our invention;

Fig. 2 is a plan of the same;

Fig. 3 is a semi-diagrammatic view of a battery installation in accordance with our invention, and

Fig. 4 is a similar view of an embodiment particularly useful as a re-run battery.

Referring more particularly to the drawings, the reference character "A" (see Fig. 1) designates a still of any desired form, the 80 form illustrated comprising a shell 1 traversed by tubular flues 2 through which hot products of combustion from the furnace pass on their way to stack 5 from the header flue 3 after having encountered the outside 85

surface of the shell in the furnace chamber
4. By thus applying heat within the body
of the oil, as well as externally, a better
heat distribution is attained with corre-
spondingly lessened localized overheating.

While this particular construction of still
is highly efficient and advantageous, it will
be understood that in the broader aspects of
the combination contemplated by us, modifi-
cations as to the type of heating of the still
are included.

From the still a vapor line 6 leads to a
fractionating, rectifying, or dephlegmating
tower 7 having in its internal construction
15 transverse partitions or plates with open-
ings, with or without vapor-distributing
caps and with overflow tubes, the condition
being that at each partition the vapors are
bubbled through a layer of the liquid there-
20 on. A simple form of such partition is
made of die-stamped slotted sheet metal or
advantageously of woven-wire fabric of de-
sired mesh, the material being iron, alumi-
num, Monel metal, nickel or other metal as
25 preferred.

Vapor connections 8 lead from the tower
to a condenser 9, preferably a partial con-
denser, constructed for example with tube-
sheets near each end and tubes extending
30 therebetween for the passage of vapors and
pipe connections 16 and 18 to the liquid
space about the tubes, for a purpose to be
referred to later more in detail. From the
partial condenser a vapor-pipe 10 leads to a
35 water cooled light worm condenser coil 11
from which pass connections to a receiver.
From the partial condenser a reflux pipe 13
leads to the top of the tower 7 for carrying
condensate back thereto and from the bottom
40 of the tower a runback pipe 14 leads to the
still.

In the use of the apparatus as described
crude oil or a distillate requiring re-running
for closer fractionation is heated in the still.
45 Vapors rising therefrom proceed to the
tower and pass up through the openings and
bubble through the layers of liquid which
soon collect on the plates. In bubbling up
50 through the layers of liquid, heavier con-
stituents of the vapors condense and join
the liquid and at the same time any lighter
constituents in the liquid are vaporized and
pass on up.

By these successive exchanges, on plate
55 after plate, the vapors are averaged closer
and closer on boiling point range and the
reflux also is successively reduced. Vapors
leaving the tower proceed on through the
tubes of the partial condenser where a por-
60 tion of the constituents are condensed out
and the vapors then pass to the light con-
densing worm. The partial condenser fur-
nishes an adequate washing reflux to the
tower, the condensate flowing down through
65 the pipe 13 to the top of the tower. In so

far as affects the function of the tower, a
total condenser may be employed at this
point, so much of the condensate as is re-
quired being refluxed to the tower and the
balance being run to a receiving tank. In
70 working with components of such close boil-
ing point, we have found it to be of im-
portance in order to produce desired frac-
tions whose boiling points lie substantially
completely within a predetermined range to
75 provide reflux in quantity greater than
would be furnished by the operation of the
tower itself, and in dealing with usual
stocks it is advantageous to calculate for
one to two parts of reflux for each part of
80 distillate; that is, the heat abstraction is suffi-
cient to condense from one-half to two-
thirds of the total vapors passing from the
top of the tower. Proper regulation of the
temperature of the refluxing condenser may
85 be secured by a suitable cooling medium, as
water, but having regard for the co-opera-
tive functioning of the whole system we pre-
fer to use the feed oil, this entering through
pipe 15 and 16 (by-pass 17 being shut) and
90 circulating about the vapor tubes. By using
the by-pass 17 for by-passing cold feed oil in
excess of that required to hold the con-
denser at the desired temperature, a con-
venient and close regulation of the quan-
95 tity of reflux may be attained. The oil flow-
ing away by pipe 18 is sufficiently raised in
temperature to be admitted to the still.

A fraction heavier than the end product
obtained in condenser coil 11 may also be
100 collected if desired by the pipe 12 from the
tower above the feed plate and leading to a
suitable water-cooled coil.

With the equipment described, distilla-
tion can be carried on by batch or continu-
ous operation as desired. In batch opera-
tion, successively higher boiling cuts may
be obtained, each of self-contained range.
In continuous operation, the feed being sup-
plied at the same rate that distillate and
110 bottoms are removed, the product will be
of uniform character, and will boil over a
predetermined range dependent upon the
outlet temperature of the top of the tower,
and the utility here lies in the completeness
115 with which the light fractions are stripped
from the bottoms and vice versa. In con-
tinuous running the feed may be admitted
to the still or preferably it may be admitted
part way down the tower by a connection 19
120 in which case it is largely stripped of light
fractions before reaching the still. This
procedure insures a high initial boiling
point of the bottoms.

From these illustrations it can be seen
125 that the running conditions may be varied as
required to be closely adapted to the stock to
be handled and the products to be made.

An advantageous embodiment of our in-
vention in a continuous crude battery in-

stallation is shown in Fig. 3. In this, there is arranged a heating coil 37 mounted in a suitable furnace and heated thereby, a series of stills 21 to 25, or as many as desired to make up a given battery, being connected by a flow line 48, and each still provided with appropriate overhead equipment. In the example shown, this comprises, for still 21, a vapor line 26 leading to a fractionating tower 31, a line 38 from thence to a partial condenser 39, and a final condenser therebeyond, not shown, for simplification; for still 22, a vapor line 27, tower 32, partial condenser 41 and similarly a final condenser 15 therebeyond, not shown; for still 23, a vapor line 28 leading to a partial condenser 33 and a final condenser, not shown; and similarly, for stills 24 and 25, vapor lines 29 and 30 respectively leading to partial condensers 34 and 35, and final condensers, not shown. The stills 21-25 are heated by any suitable means and at progressively higher temperatures from still to still in accordance with the distillates to be taken off.

25 The operation for this is as follows: The crude oil is supplied by pipe 47, passes into partial condenser 39, circulating about the vapor tubes thereof, and out by pipe 40 to partial condenser 41, thence by pipe 42 to partial condensers 33, 34 and 35 in succession, thence by pipe 36 to the heating coil 37 where it is raised to the requisite temperature, depending upon the stock, and is then introduced into the fractionating tower 31, 35 for example about midway. Lighter fractions vaporized pass on up the tower, and the lightest constituents thereof proceed to the partial condenser (being cooled therein to the proper point by the heat interchange 40 with the feed oil which is regulated in amount by the by-pass) and then go to the final condenser. The unvaporized portion and reflux flow down from plate to plate and along the pipe 26 to the still. Liquid condensed in the partial condensers 39 and 41 returns to the towers through pipes 43 and 44.

45 Vapors rising from still 21 are also fractionated and sorted in the tower. The residual oil from still 21 flowing by a suitable fixed-level outlet is picked up by a pump 49 and forced into the tower 32 where it is stripped of its lightest content and passes down to the still 22 where it is further heated and vapors are given off to the tower for fractionation. The residual oil from still 22 passes to still 23 where it is further heated and vapors are given off to the condenser system. The residual oil from still 23 passes on in succession to the remaining stills in the battery, being progressively heated and relieved of vaporizable constituents for the respective temperatures maintained.

65 We have illustrated the fractionating

towers as applied to the stills of the light end of the battery, as in general it is here that a sharp separation is desirable and especially useful; we contemplate, however, combining the fractionating tower arrangement in with any or all stills where it is desired to specialize on a sharp primary separation.

Our invention is very advantageous in re-running the overlap in cuts previously taken by overhead equipment of the usual type, as for example the overlap between naphtha and water white distillate. As an example of an installation convenient in such connection, attention is directed to Fig. 4, in which is indicated a still 51 suitably heated and with vapor line 53 to a tower 54, a vapor pipe 55 therefrom to partial condenser 56 and final off-take 57 in turn to condenser 58. A reflux pipe 59 connects from the partial condenser 56 back to the top of the tower 54 and from the bottom thereof a run back pipe 60 leads to the still. A second still 52, suitably heated at a higher temperature than still 51, has an analogous vapor-line 61, tower 62, vapor-pipe 63, partial condenser 64, final off-take 65 and condenser 66; also a reflux pipe 67 from the partial condenser, and a run back pipe 68 from the tower. Additional stills may be combined in this battery if desired, but we regard a two-still unit as generally desirable for straight re-run duty.

With this installation the feed is supplied from line 69 by pump 70 through the line 71 to the partial condenser 56, circulates about the tubes therein, passes thence by pipe 72 to the partial condenser 64 and thence by pipe 73 to the tower 54 and thence by the reflux run back 60 to the still. This still with its overhead equipment removes the naphtha, and the bottoms are then passed by pump 75 and line 76 to the second tower 62 and proceed therefrom by the run back pipe 68 to the second still 52. This still with its overhead equipment removes the water white. The bottoms from the second still pass through a pipe 77 to a cooling coil 78 and pump 79 to the gas oil tank.

As an example, on a refinery re-run stock, the first still removed all of the naphtha, an overhead of 40%, and the bottoms on being passed to the tower and second still gave up all the water white, an additional 45%; the bottoms therefrom was a gas oil wholly devoid of lighter fractions.

Having, in the foregoing, referred to hydrocarbons of the character of petroleum, it is to be observed that such expression designates not only petroleum proper and its derivatives, but also other oils containing hydrocarbons of this character, such as shale oils, lignite oils, brown-coal oils, and low-temperature oils retorted from carbonaceous material.

While in describing our invention we have referred to certain specific examples of equipment and procedure, it will be understood that these are illustrative and not 5 limitative. Nor is the invention to be understood as dependent upon the accuracy of any theories or reasons suggested to explain the advantageous results. On the contrary, the invention is to be regarded as limited only 10 as defined in the following claims, in which it is our intention to claim all inherent novelty as broadly as the prior art permits.

What we claim is:

1. The improvement in the art of distilling petroleum oils having a large number of constituents of different boiling points to produce simultaneously and continuously (1) a light distillate containing substantially all the low-boiling constituents of the original oil and substantially no constituents boiling above a predetermined temperature, and (2) a residual product containing substantially all constituents in the original oil of higher boiling point than those in said 25 light distillate and substantially free from constituents of said light distillate, which process comprises continuously introducing the original oil into a fractionating zone at an intermediate point thereof, flowing the 30 oil downwardly therethrough, supplying heat adjacent the lower portion of said zone to produce a substantial amount of vapors, thereby permitting the formation of adequate reflux by condensation of such vapors, 35 conducting the vapors upwardly through said fractionating zone in countercurrent to the descending oil, the proportion of said vapors being sufficient to secure the stripping from said oil of substantially all the 40 low-boiling constituents desired in the said light distillate, so that the oil entering the heating region is substantially free from constituents of said light distillate, cooling to hold a substantially constant temperature 45 in the upper portion of the fractionating zone, while abstracting not less than that amount of heat which would be taken up by refluxing to the fractionating zone about one-half of the vapors leaving the same, 50 collecting and removing as the desired light distillate the product of condensation of the vapors leaving the upper portion of the

zone, and continuously removing from the lower portion of the zone the said residual product.

2. The invention according to claim 1, comprising continuously introducing the said residual product into an intermediate point of a second and independent fractionating tower, operating said second tower 60 under substantially the same conditions as said first tower, collecting and removing as a heavy distillate the product of condensation of the vapors leaving the top of the second tower, and continuously removing residual oil from the base of the second tower.

3. Process of continuously distilling hydrocarbon oil of the character of petroleum to obtain products having a relatively narrow range of boiling points, said process comprising distilling the oil, passing vapors therefrom through a fractionating zone, pre-heating at least a portion of feed oil passing to the distilling zone by indirect heat exchange with vapors from said fractionating zone, thereby partially condensing such vapors, introducing the preheated feed oil into an intermediate portion of said fractionating zone and flowing it downwardly therethrough in contact with ascending vapors, regulating the amount of condensation by by-passing to the fractionating zone any portion of the feed oil in excess of that required in said heat exchange, and condensing vapors passing from the partial condensation zone.

4. Process for the fractional distillation of hydrocarbon oils of the character of petroleum, which comprises distilling the oil in a plurality of series-connected zones, 90 fractionating vapors from each zone, pre-heating feed oil by passing it in indirect heat exchange with vapors issuing as a final product of such fractionation, whereby such vapors are partially condensed, diverting the feed oil to or from the partial condensing zones to regulate the amount of condensation, passing the preheated feed oil into an intermediate portion of the first fractionating zone, and forwarding residual oil from each 100 distilling zone to the fractionating operation of a succeeding distillation.
